UNITED STATES PATENT OFFICE.

JOHN H. MACMICHAEL, OF TOLEDO, OHIO, ASSIGNOR TO CONCRETE MIXING AND CONVEYING COMPANY, OF CHICAGO, ILLINOIS, A CORPORATION OF ILLINOIS.

MECHANISM AND PROCESS FOR MIXING AND TRANSPORTING CONCRETE AND SIMILAR MATERIALS.

1,185,117.

Specification of Letters Patent.

Patented May 30, 1916.

Application filed September 6, 1910. Serial No. 580,582.

To all whom it may concern:

Be it known that I, JOHN H. MACMICHAEL, a citizen of the United States, residing at Toledo, in the county of Lucas 5 and State of Ohio, have invented certain new and useful Improvements in Mechanism and Processes for Mixing and Transporting Concrete and Similar Materials, of which the following is a specification, reference being 10 had therein to the accompanying drawing.

This invention relates to improvements in mechanisms for mixing the ingredient materials (rock, sand, cement and water) of concrete as used in making artificial stone 15 and kindred bodies, and for rapidly conveying them during the time of mixing, to distant points, the simultaneous mixing and conveying being effected pneumatically.

It also relates to improvements in the 20 methods or processes followed in handling such materials.

The objects of the invention are to produce a superior final product, to expedite the producing and delivering of the composite materials, and to economize in the 25 manufacture.

Of the accompanying drawings: Figure 1 is a view partly in elevation, partly in section, showing conventionally, and somewhat diagrammatically, an apparatus composed of parts by which the invention can be carried out. Fig. 2 is an elevation also conventional and diagrammatic, illustrating more completely such an apparatus. 35 Fig. 3 is a fragmentary view similar to Fig. 1, but showing a modified form of receptacle. Fig. 4 is a view, mainly in plan, of the main receptacle and of the collector in Fig. 1. Fig. 5 is a partial cross section 40 of the main discharge pipe, the parts being shown on a large scale. Fig. 6 is a longitudinal section of part of the main discharge duct. Fig. 7 is a cross section of the same.

45 In the drawings, 1 represents a receptacle into which are fed, the materials which are to form the composition. And for present purposes I will assume that the composite material is to be of the nature of ordinary concrete. To produce it, predetermined proportioned quantities of cement, sand and broken rock are brought together in this receptacle. They are respectively contained 50 in initial holders, 2, 3, 4. Each of these has

a tube or pipe connecting it with the main 55 receptacle 1, these being shown at 5, 6 and 7. With the materials above specified, there is supplied also the proper quantity of water, this brought from a tank such as indicated at 8.

The main receptacle 1, communicates with and terminates at its end in a delivery conduit 9. This is extended to the point where concrete material is to be finally placed, as will be more fully described below, and is 60 made and arranged in either of several ways. This receptacle 1, including the initial wider vertical part and the bend, curve or elbow at the bottom, may be made in one piece, as shown in Fig. 1, or in two or more 70 pieces, as shown in Fig. 3, where the curve or elbow part is indicated as bolted to the vertical part.

The introduction of the initial materials, and the mixing of these and the water, as 75 well as the propelling or transporting of the concrete mass, are caused by the following means: 10 indicates a receiver for compressed air. It is illustrated conventionally, as is also an air compressing mechanism at 80 11. The air is drawn by suction through ducts or pipes 12, 12^a from the interior of the main receptacle 1. When the dampers or controlling devices at 13, 14, 15 in the tubes or pipes, 5, 6, and 7 respectively are 85 properly adjusted, the air which enters at the orifices 16 of the pipes 16^a, causes the passage of the respective materials through the pipes to the receptacle 1. They are 90 dropped from the air current, the air escaping from the receptacle through the aforesaid pipe 12. To guard against any dust, or particles foreign to the air, being carried with it to the compressor or other parts, a collector is employed such as is conventionally illustrated at 20. The air from the receiver is taken through a pipe 21 to a main 21^a from which it can be carried by pipes to the places desired. One body of air is carried to the water tank 8, through 100 a pipe 8^b, from which the water is forcibly ejected under pressure through pipe 8^a. The pipes or ducts 5, 6, and 7 are so arranged as to deliver their materials at points where they can be impinged upon by the incoming stream of water. As shown in the drawings, their delivery ends are in the arc 105 of a circle and the water supply pipe is tan-

gential to the circle so that the water causes a whirling or gyratory motion of the particles of the masses, not only insuring that they shall be moistened, but, to some extent, initially commingled.

That the action of an apparatus of this sort may be understood, and the method of manipulating the materials, I will call attention to what I understand to be the physical and chemical characteristics of the materials for the handling of which the mechanism was designed. Those bodies which are used as the principal ingredients of the composite masses for producing artificial stone or rock are found in one or another crystalline, or analogous form. They are held in such form while they include a quantum of water, to-wit the water of crystallization. In preparing them for use in producing the artificial bodies referred to, they are subjected to heat for the driving off or disassociating of one or another undesirable bodies, this heat resulting in breaking down the crystalline structure and driving off the water of crystallization. When, at a later time, they are to be used for forming artificial rock bodies, their tendency to again crystallize in the presence of water is availed of. To a given quantity of such material (either alone, or in mixture with other bodies) a corresponding proportionate amount of water is added. Immediately upon the water coming in contact with the particles of material, its crystallizing action again commences, this resulting finally in its hardening or "setting." If the crystallizable material is physically mingled with others prior to this, they also are bound together by the crystallizing, and, after the mass has hardened or set, constitute parts of the final hard or rocklike composite. If after the particles of water commence their action upon the particles of crystallizable material the mass, as a whole, or any parts thereof, is agitated by shaking, stirring or the like, the total "setting" or hardening efficiency is reduced correspondingly, first from the fracture and breaking up of the smaller initial crystals and, second, by interfering with the cohering of crystal with crystal throughout the mass. It will be seen, then, that there are two requisites for the production of artificial bodies of this class, of a most superior character; first, that the water should be distributed through the mass in the shortest possible period of time, and, second, that this distribution of the water through the mass of crystallizable material, when used alone, or through the composite mass of that material, and any others that may be added, should be accomplished with the least agitation possible; or, that, where agitation is required it should be performed as near instantaneously as possible.

Heretofore the mixing of mortar, concrete, cement, gypsum and the like bodies has been accomplished without bodily movement, by means of jets of fluid such as air or steam or by mechanical mixing devices of one sort or another, such as spiral mixing blades in troughs, or rotary cylinders or drums, sometimes with and sometimes without mixing or beating arms, or structures similar in general character to these.

I have succeeded in mixing large masses of concrete and like materials in a few seconds, four or five, and also simultaneously delivering the finally mixed composite mass almost instantaneously to distant points, one hundred feet or more in some instances, where it can be immediately put in the position where it is expected to harden into rocklike form immediately after the water has been brought into contact with the crystallizable ingredients.

I do not limit myself to the details of structure which I have shown in the accompanying drawings, as I have carried out my process in mechanisms of various forms; those appearing in the drawings being selected as types and for the purpose of giving a complete understanding of what is accomplished by such devices when operated in the described manner.

By assumption, the hoppers or bins at 2, 3, 4, respectively contain, cement, of any known constitution, sand, and reduced rock. By opening the valves or slide dampers at 13, 14, 15, these separate ingredients can be allowed to pass down to their several conduits 5, 6, 7, in any desired proportions. Each of these conduits, as aforesaid, has an air inlet at 16, so arranged and directed that the incoming jets of air will carry the streams of materials along the ducts and down into the main receptacle 1. Here the principal parts of the solid matter will settle, while the air body is drawn out and on through the outlet duct at 12 12^a toward the air compressor 11. As the smaller dry, or dustier, particles of the cement, sand and rock may be suspended in the air current and carried with it into the outgoing duct, I prefer to insert into the air passage a dust-collecting apparatus. There are numerous forms of collectors that can be used for this purpose. One is shown at 20 of a well known type, into which the air enters initially, on tangential lines, as shown in Fig. 4, the whirling of the air in the collecting chamber causing the dusty particles to settle. The cleansed air is taken to the outlet part 12^a of the duct to the compressor. After compression it is received in the receiver 10, which, together with the compressor, may be of any preferred character.

Returning to the points where the cement and other solid materials are initially introduced; I prefer to deliver the requisite

water simultaneously as they enter. This may be done by delivering periodically separate amounts of water proportioned in number and quantity to successive parts of the mixture of solid materials. But I prefer to deliver a continuous regulated and measured stream of water in such way that its mechanical action, when entering, can be utilized to effect at least an incipient mixing or mingling of the solid body. I employ a water tank 8, situated either at a relatively elevated position, where the head of the water can be used to drive it somewhat forcibly into the receptacle; or place it in a relatively low position and supply to the upper part of the tank a part of the body of compressed air. For example, from the receiver 10, or from the intermediate main 21^a, an air pipe 8^b, can be employed which, under the control of suitable valves, will deliver the desired quantity and pressure of air for injecting the water into receptacle 1. In the mechanism shown in the drawings this water is taken in on tangential lines and on a horizontal plane near the top of receiver 1, and so directed that the water is driven across the vertical lines, along which the cement and other bodies are dropping. This causes the incoming solid materials to become mingled, and also insures that the water shall, to some extent, be quickly distributed through the general mass. But the principal agency in effecting the rapid mixing of the water with the crystallizable particles, and uniformly commingling all of the solid bodies, is a mass of compressed air, delivered in such way as to forcibly and rapidly drive the solid masses out of receptacle 1, and along an elongated duct, which latter, as will be noticed below, is also used for supporting and guiding the material to the more or less distant point, where it is to be placed in position for hardening or "setting." To accomplish these results a body of compressed air is taken into the receptacle 1, and delivered at points above a part of, or the entire, mass. A mechanism like that in the drawing delivers such a body of air in the form of a powerful jet, which enters from the receiver 10, or from an intermediate main 21, through the air duct 22, which is opened, closed, and controlled, by the valve at 23. As seen on examining Fig. 1, the air enters in a direction tangential to the lines of movement of the bottom of the mass in the receiver 1,—and drives it laterally out from the lower end of the receiver, and then through and along the trunk or duct at 9. As the lower parts of the mass or body in receiver 1, are successively expelled by the blast, the upper part of the mass rapidly settles into the pathway of the incoming air, that is, settles downward toward the nozzle at 24, thus rapidly continuing the feed to

the air. I construct the receptacle 1, particularly the lower part of it, in such way that the vertical walls will not act to confine the mass or cause choking thereof in its downward movement, this part of the apparatus differing in this respect from those which I have heretofore made, in which the walls were so tapered as to cause the particles or different parts of the entire mass to converge toward a central axis, the earlier apparatus referred to being designed to have two air bodies delivered to it, one near the top, and one near the bottom, the upper body of air being intended to push or drive the material downward to continuously feed it into the path of the lower jet. In the present instance, this part of the mechanism is so designed that the feed of the material will be readily caused by its gravity, and the walls of the receptacle so shaped and related that they will not impede its downward movement. The wall 1^a, is approximately vertical, though, by preference, it tends to curve outward or away from the vertical, so that the material can move easily without obstruction.

The best results are attained by having the delivery pipe 9 of a relatively large diameter so that there shall be freedom for these relative movements of the rock particles and of the submasses that are forcibly impelled ahead of the air jet. The delivery pipe itself becomes a mixing chamber wherein pneumatic mixing is effected or continued, and, if this duct is of a size properly related to the other parts, and to the sizes of the particles of the materials, the latter can be rapidly impelled through it without danger of clogging or choking. The engineer, in any instance, will readily understand what the relative proportions of the parts should be; but I have found that for concrete with, as aforesaid, its masses or relatively large rock pieces, the diameter of the delivering and mixing pipe 9 should be from six to ten inches, the latter generally preferable, this being in contrast with the relatively small delivery tubes frequently used in pneumatic apparatus, and not designed, as described, to permit such relative motions of large component particles as will insure perfect mixing.

Considering the confined region extending from the top plane of the material in the receptacle 1 down through that receptacle, and then through and along the duct 9 to its discharge exit as a path of movement for the material, it will be seen that this path is, at one or more places, partially obstructed or reduced. Thus, the escape orifice at the bottom of the receptacle 1, provided by converging the walls of the receptacle to the entrance orifice of the duct 9, can be regarded as a partial obstruction, which acts to bring all the particles of the several masses

in the receptacle 1 to a reduced passageway, and this assists in the mingling of the masses and also assists in delivering them properly to the air jet at the end of the duct. Again, the elbow or bend in the duct immediately below the receptacle is, to some extent, an obstruction in the path of the material, which assists in breaking up the masses as they impinge upon it, and enables the air blast to get an effective hold upon the particles, to insure their propulsion and further mingling.

I do not mean to exclude the use of a body of air delivered to the upper part of the receptacle 1, above the mass of contents; for, if desired, such air can be introduced through a duct at 32 controlled by a valve 33. Indeed, under some circumstances, the body of air so delivered at 34 can be depended upon to accomplish the entire work of expelling the mass from the receptacle, and driving it along the delivering and mixing duct at 9. When air is delivered through both the ducts 22 and 32, the upper air body is distributed over a wide surface area and presses downward on the whole mass, while the air passing through the duct 22 is delivered as a reducted jet at a point where the resistance offered by the material is least and where this jet, because of its velocity, can effectively work against the small sub-masses of the material at the escape end of the receptacle. The upper air body, therefore, has the function of aiding the downward movement of the mass into the range of action of the lower jet and toward the outlet opening.

In the preceding paragraph I have referred to the upper air body as desirable in aiding the escape of material from the receptacle, but it is to be understood that in some cases and for some classes of work this upper air body may be omitted and the entire work of conveying and mixing effected by the single air jet near the bottom of the receptacle.

Turning now to the action of the air and of the parts of the mechanism that act on the material after it leaves the receptacle 1: The mechanical action of the air is such that as the particles of rock, and sand (when they are present) are rapidly whirled and agitated along the duct. And at the same time the cement and water being quickly brought into the contact necessary for crystallizing are coated upon these solid particles, which, as is well known to those practically acquainted with this work, is a necessity for perfect results. The reader has, doubtless, frequently observed, at places where concrete was being mixed, that large sub-masses of the rock, sand, etc., were, (even after the various constituents of the general mass had been subjected to prolonged shoveling, agitating and rolling in mechanical mixers)

still unaffected, that is were still with clean surfaces, frequently not even being moistened; and has further observed operatives with tools, brooms, or like implements, applying to such yet clean particles or masses, a thin mass of water and suspended cement, the brooms being used to insure especial coating of these surfaces which have escaped from the desired action of the cement and water while going through the preceding treatment as parts of the general mass.

Materials passing through an apparatus such as herein shown and described and handled in the way set forth is thoroughly coated, as to all of its particles, pieces of rock, etc., with the cement mass and the larger and the smaller particles are uniformly distributed throughout the delivered mass as an entirety. This results from the action of the air compelling such uniform distribution of the water that the thick moistened mass is carried through in uniformly constituted sub-masses. If three materials such as cement, sand and reduced rock were to be driven by an air-blast through a conduit while in a dry condition, the tendency would be for the light dry particles to be driven through first, and for those of the next grade in specific gravity, to be carried through as a second mass, such as the sand, separately from the cement, and for the rock pieces to be carried through as a still separated third mass. But inasmuch as the water and cement are introduced into the receptacle 1, they, by the time they leave that part of the apparatus, have commenced to adhere to the larger and heavier particle, and have commenced to form a general mortar-like mass, the consistency of which not only prevents the differences in specific gravity from separating one mass from the other while under the air blast, but on the contrary compels them to so intermingle that at the place of delivery it is found that a concrete body passing through this apparatus is thoroughly and completely mixed. Within a few seconds from the instant when the dry rock, cement and sand are brought together in the receptacle 1, and after the instant when water is supplied, the thoroughly mixed concrete is at the place of deposit and ready for "setting" before the crystallizing action above referred to has commenced.

To assist in the mixing of the different masses among each other, as they are traveling through the duct, I prefer to provide the latter with devices such as spurs or sharp projections which, while offering no serious impediment to the rapidly advancing mass, break up any clots or large lumps to insure a more thorough mixing. Or, use can be made of a conduit such as I have shown in the drawings; this being a pipe or tube formed of sheet metal coiled

or wrapped spirally and having its overlapping edges secured together by headed rivets. These spirally arranged rivets and the spirally extending edges of the sheet 5 provide what may be termed a rifled path for the material, so that as it advances under the action of the blast, it is compelled to whirl spirally insuring that the particles shall be rolled over and over and thoroughly 10 coated with cement and intimately commingled. Metallic tubes or pipes for such purposes are susceptible of rapid cutting and wearing because of the abrasive action of the sand and rock. This I effectually obviate by applying to the inner surfaces of 15 the thin pipe metal a coating of non-abrasive material. By preference I use an asphaltum paint or coating. It can be applied by a brush or by immersion. I have 20 succeeded in applying liquid bituminous substances by means of the air blast itself. A coating of this character protects the surface of the tube or pipe from the cutting action of the sand and rock even at those 25 places, such as the bends where the impingement is the most violent for a long time.

It will be understood that while a pipe such as I have shown having the inward 30 projecting rivet heads and the inward exposed plate edges is for some reasons preferable, the invention is not so limited, and a pipe with a smooth interior surface can be used.

35 The main pipe 9, may be connected in any suitable way with branch pipes such as at 30, and of the latter there may be any desired number, one extending in a horizontal direction, for example, as to the lower floor 40 of the building, and another extending to a higher floor. Between a series of branch pipes of such sort and the main duct, use may be made of a cutoff and deflecting valve 45 device 29 of any suitable sort so that the stream of concrete or other material may be at one moment directed through one of the branch ducts, and at the next moment through another.

In Fig. 2 I have shown how the principal 50 parts of an apparatus such as above described, can be mounted upon a truck or vehicle frame so as to be ready for transportation from one place to another.

I do not herein claim any of the subjects 55 matter covered by the claims in my copending application 642,400, filed August 4, 1911, the claims in said other application relating to the process of mixing and treating the ingredients of concrete and conducting them 60 while being so mixed and treated.

The mechanism herein shown is characterized by having an immediate delivery of the material from the initial receptacle to the mixing and conveying duct and having it 65 immediately impinged upon by the air that

passes through the wall of the elbow-like section or duct. The interior of the receptacle, the elbow and the mixing and conveying duct are unobstructed; there is no impeding of the rapid passage of the material, and there is no catching or clogging of the concrete. The air is delivered directly into the initial end of the mixing duct so that it acts with the utmost efficiency.

What I claim is:

1. The herein described method of treating building material as concrete and the like, composed of two or more initial ingredients, which consists in conveying regulated quantities of the said ingredients to a 70 receptacle by air currents, directly depositing the said ingredients in the receptacle, drawing the said air into a compressing mechanism and then delivering the air, under pressure, into contact with the materials in the said receptacle and pneumatically mixing and discharging the agglomerated mass therefrom, substantially as set forth.

2. The method of preparing concrete-like 90 building material composed of two or more initial ingredients, which consists in conveying to a receptacle regulated or measured quantities of said ingredients by currents of air, delivering to the said receptacle measured or regulated quantities of water, withdrawing the air of the said currents from the receptacle, subjecting it to the action of compressing mechanism, and delivering bodies of the said air after compression where- 95 by there is effected a discharge of the ingredients from the receptacle and an intimate mixing and intermingling of the ingredients along an extended path of movement.

3. In a concrete mixing and conveying device, the combination of a receptacle, a conduit leading therefrom, the conduit being formed of spirally wound metal sheets having exposed inner edges, and means for rapidly forcing material from the receptacle 110 through the conduit whereby it is engaged by the edges of the spirally wound sheets and intimately mixed, substantially as set forth.

4. In a concrete mixing mechanism, the combination of the mixing and conveying duct, the initial receiving chamber closely adjacent to the mixing duct and adapted to receive the ingredients of concrete, such as 115 rock pieces, sand, cement and water in separate masses proportioned to constitute concrete, the short curved elbow-like duct connecting the receptacle immediately to the mixing duct, the air pipe on the outside of the receptacle and of the elbow duct, the air orifice in the elbow duct arranged to deliver air directly in the receiving end of the mixing duct, and the air duct communicating 125 with the upper part of the receptacle for de- 130

livering a relatively large body of air thereto.

5. In a concrete mixing and conveying mechanism, the combination of the elongated mixing duct of relatively large diameter, the initial receptacle narrowing in diameter to the diameter of the mixing duct, the short elbow-like duct connecting the receptacle immediately to the mixing duct, the 10 devices for delivering an air jet from the outside of, and through the wall of the

elbow duct to the initial end of the mixing duct, and the devices for delivering a body of air under pressure to the upper part of the initial receptacle.

15

In testimony whereof I affix my signature, in presence of two witnesses.

JOHN H. MacMICHAEL.
